UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,807, dated March 14, 1882.

Application filed February 11, 1882. Term of patent 3½ years.

To all whom it may concern:

Be it known that I, HENRY HORAN, of East Orange, in the county of Essex and State of New Jersey, have invented a new and original

5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is filled with small forms, resembling broken twigs and short lines and dots, and is traversed by various flower groups, as follows:

10 *A* is a cluster having a central star-shaped flower on a background of leaves, a fern above and one below, several small branching twigs, and a small flower-and-leaf cluster projecting on the right.

15 *B* is a larger group of circular and star-shaped flowers on a ground of leaves, with projecting ferns and leaves and twigs or lichen-like forms traversing loosely the surrounding field.

20 *C* is a flower-and-leaf group, with a projecting flower-and-leaf spray above, and a flower, leaf, and bud spray to the right, and branching twigs or lichen-like forms springing out on every side.

25 *D* is a group consisting of the central leaf cluster, *d*, with projecting twig forms and a leaf spray above, below and on the left the scattered leaf-and-flower cluster *b*, bearing buds and branching twigs, and on the right below the scattered cluster *e* of flowers, leaves, and twigs.

30 *E* is a group similar to *B*.

35 *F* (shown in part on each side of the photograph) is a small cluster of flowers and leaves, with projecting twigs or lichen-like forms and a leaf-sprig on the right.

40 *G* (shown in part at each end of the photograph) is a flower-and-leaf-cluster, with projecting sprays and twigs, and just below it a smaller cluster, *H*.

45 *K* (shown in part in the four corners of the photograph) is a leaf-and-flower cluster, with fern and leaf sprays above and projecting twigs or lichen-like forms.

50 The design as a whole presents an open appearance.

I claim—

55 1. The design for carpets, consisting of the group *A*, substantially as shown.

2. The design for carpets, consisting of the group *B*, substantially as shown.

3. The design for carpets, consisting of the group *C*, substantially as shown.

4. The design for carpets, consisting of the group *D*, substantially as shown.

5. The design for carpets, consisting of the group *F*, substantially as shown.

6. The design for carpets, consisting of the groups *G H*, substantially as shown.

7. The design for carpets, consisting of the group *K*, substantially as shown.

8. The design for carpets, consisting of the groups *A B C D E F G H K*, substantially as shown.

65 9. The design for carpets, consisting of the groups *A B C D E F G H K* and the ground *a*, substantially as shown.

HENRY HORAN.
